(57) **CLAIM**

The ornamental design for a connector box for television receiver, as shown and described.

DESCRIPTION

FIG. 1 is a front perspective view of a connector box for television receiver, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 2;

FIG. 11 is an enlarged view of the encircled portion 11 in FIG. 8;

FIG. 12 is a front perspective view thereof in a TV stand environment; and,

FIG. 13 is a front perspective view thereof in a television receiver environment.

The even-dash broken lines illustrating portions of the connector box for television receiver form no part of the claimed design. The even-dash broken lines illustrating portions of the TV stand in FIG. 12 and the television receiver in FIG. 13 form no part of the claimed design. The
